(57) **CLAIM**

The ornamental design for a bicycle rack, as shown and described.

DESCRIPTION

FIG. 1 is a perspective top and front view of a bicycle rack showing my new design;

FIG. 2 is a top view of FIG. 1;

FIG. 3 is a bottom view thereof; and

FIG. 4 is a front view thereof; and,

FIG. 5 is a rear view thereof.

The broken-line disclosure of a portion of a wall in FIG. 1 is for illustrative purposes only and forms no part of the claimed design.
